CONTROL MECHANISM

Harold L. Haynes, deceased, late of West Chicago,
Ill., by Phyllis C. Haynes, administratrix, West
Chicago, Ill., assignee to Phyllis C. Haynes

Application December 21, 1932, Serial No. 648,178

7 Claims. (Cl. 161—1)

This invention relates to a control mechanism and has special reference to time-controlled switches, and the like, which may be automatically actuated at definite and variable time intervals.

More particularly, this invention relates to a time-controlled switch mechanism having an actuating member for operating a switch, and control mechanism for regulating the movement of said actuating member.

One of the objects of this invention is to provide an improvement form of actuating mechanism capable of using with a snap switch, or the like, which mechanism may be controlled by a clock and bears a very simple mechanical relationship with the switch itself.

Another object of this invention is to provide an escapement mechanism connected to the actuating member which may be intermittently operated at definite and variable time intervals by a clock or other time-controlled mechanism.

A further object of this invention is to provide a housing comprising two separable halves; one of which halves contains the switch itself and all 25 of its associated mechanism, conducting wires, etc., the other of which halves contains all of the time-operated mechanism which actuates the switch at definite and controllable intervals.

Still another object of this invention is to provide a time-controlled mechanism that, while engaging the levers of a snap switch, is otherwise entirely disconnected from the switch.

Further objects and advantages will be apparent from the following description taken together with the accompanying drawings in which latter:

Figure 1 is a front plan view of a time-controlled switch embodying the present invention;

Fig. 2 is a vertical, cross-sectional view taken on line 2—2 of Fig. 1;

Fig. 3 is a partial rear elevational view showing the actuating member and gears associated therewith;

Fig. 4 is an exploded perspective view of a portion of the escapement mechanism which is connected to the actuating member;

Fig. 5 is a plan view of the wheel-end of the escapement mechanism shown in Fig. 4 in contact with the star-wheel and disc forming the rest of the stop member, both portions being in position to prevent movement thereof; and

Fig. 6 is a view similar to that shown in Fig. 5 with the elements in changed position in the act of rotating to permit movement of the actuating member.

Referring more particularly to the drawings,

there is shown a two-part casing comprising housings 1 and 2 so constructed as to allow them to be attached to each other to form a complete unitary for both the time-controlled mechanism and the switch.

As shown in the drawings, housing 1 holds the time mechanism which may take the form of a clock, and will so be referred to hereinafter, and housing 2 holds the switch proper.

Referring to Figs. 1 and 2, it will be seen that the housing 1 has a hinged door 3 at its forward side. This door is provided with a glass or other transparent window 4 through which the time-indicating and control-indicating hands, dial, etc., are visible. Means for tightly closing the door 3 as, for instance, by a screw 5 is provided, and preferably a gasket of water-proof and dust-proof material is placed between the door and the body of the housing 1 to prevent access of dust and moisture. In order to fasten the housings together, the rearward housing 2 is provided with two forwardly projecting male screws (not shown) which extend almost to the forward interior surface of the housing 1. Suitable female screws 6, fastened through openings in the front surface of housing 1, engage the forwardly projecting screws and serve to hold the housings and their therein contained mechanism in proper relationship. The screws 6 having solid slotted heads effectively seal off the housing 1 against admission of dust and moisture. It will thus be seen that the assembling of the two housings is an exceedingly simple operation and consists merely in placing the housing 1 against the cooperating edge of the housing 2 thereby properly centering the screws with the holes through which the female screws pass and thereby inserting and tightening the screws 6.

Referring to Fig. 2, a standard form of electrical snap switch 7 is shown fastened to the interior rear surface of housing 2. The snap switch may be of any usual make, except that in place of the button or knob usually found on snap switches there is provided a double-lever 8 which is keyed to the shaft 9 of the switch so that on moving lever 8 the shaft will be rotated. It is also to be understood that there is the usual form of restraining spring within the switch so that the same will suddenly and rapidly change its position when the shaft 9 is rotated a sufficient distance. As this construction is well known in the art of snap switch construction, the same will be understood without further description.

The one essential difference in the present switch is that the lever 8 replaces the ordinary

knob. This lever, which has two oppositely disposed arms extending outwardly from the shaft 9, makes it possible to operate the switch by the controlling mechanism whose release is actuated by a clock in the housing 1.

The clock 10 is fastened to the interior of the housing 1 by means of screws 11. This clock may be of standard construction and may be similar to an alarm clock. As the clock may be of standard construction, only such elements thereof will be described as is necessary for an understanding of the present invention.

Main spring 12 is preferably employed to operate the switch-turning mechanism as well as the clock itself. The main spring shaft 13 may be shaped at one end to fit a key to be used in winding the same, and a gear 14 may be loosely mounted on the opposite or rear end thereof.

A ratchet 15 is fixedly mounted about the main spring shaft 13 adjacent gear 14. A pawl 16, pivotally mounted at 17 to gear 14 and held adjacent the ratchet 15 by spring 17a, permits the main spring 12 to be wound up by rotating the main spring shaft 13 without causing any movement of gear 14, while movement of the ratchet 15 in a clockwise direction, as shown by the arrow in Fig. 3, moves the gear 14 therewith. Gear 14 meshes with pinion 18 which is connected to an actuating member or gear 19.

Actuating member 19 is provided with outwardly projecting members or pins 20 which are so positioned as to engage the oppositely extending arms of the lever 8 on shaft 9. As the main spring shaft 13, due to the action of main spring 12, tends, when under any tension, to rotate in the direction of the arrow shown on gear 14, there is a constant tendency for the actuating member 19 to rotate at all times in the direction of the arrow shown thereon.

In order to prevent rotation of the actuating member 19, except when it is desired to operate switch 7, an escapement mechanism such as is shown in Figs. 4, 5, and 6 may be employed. A portion of this mechanism is shown in Fig. 4. This may comprise a pinion 21 which meshes with the actuating member or gear 19. Pinion 21 is mounted on a stud shaft 22 on the end of which is a half sleeve 23 with a split collar 24 adjacent the jointure of the shaft 22 and the half sleeve 23. A coil spring 25 is provided with enlarged end coils 26 which are adapted to fit over the half sleeve 23 with the outwardly extending portion 27 in the groove formed between the ends of the split collar 24. A shaft portion 28, having a reduced end portion 29, is inserted within the spring 25 with the reduced portion 29 extending into opening 30 in the shaft 22 in which it is freely rotatable.

A wheel 31, having a central aperture 32 and a sleeve 33 extending inwardly therefrom, is positioned over the reduced end 29a of shaft portion 28. A split collar 34 is provided on sleeve 33 so that the projecting portion 27a of spring 25 will fit into the notch provided between the ends of split collar 34.

When the portion of the stop member shown in Fig. 4 is mounted in the clock casing, as shown in Fig. 2, with a sleeve 35 between the outer face of wheel 31 and the adjacent clock casing, a unitary structure is formed which is substantially rigid but at the same time, due to the spring 25, prevents a sudden jerking movement if one end is suddenly stopped while the member as a unit is being rotated. The advantages of this will be hereinafter set forth.

Wheel 31 is provided with a peripheral clearance notch 36 adjacent which is a dog 37. As pinion 21 meshes with the actuating member 19, the portion of the escapement mechanism just described will also tend to rotate as long as the main spring is under any tension.

In order to prevent rotation of wheel 31, a star-wheel 38 is mounted on the front clock casing adjacent wheel 31. The star-wheel may be provided with four concavely rounded sides having a radius substantially the same as that of wheel 31 so that wheel 31 may engage the star-wheel 38 as shown in Fig. 5.

A disc 39 is fixedly secured to the face of said star-wheel away from wheel 31, or, in other words, to the rear side of star-wheel 38. Slots or grooves 40 extend inwardly from the periphery of disc 39 at an angle to the radii thereof in a direction opposite to the direction of rotation of said disc which is shown by the arrow in Fig. 5.

As shown in this figure, dog 37 is on the lower face of wheel 31. Thus, when the periphery of wheel 31 engages one of the concave surfaces of star-wheel 38, wheel 31, due to the action of main spring 12, will rotate in the direction shown by the arrow thereon until dog 37 comes in contact with the periphery of disc 39. When this occurs, further rotation of wheel 31 is prevented until star-wheel 38 and disc 39 are moved in the direction as shown by the arrows. Upon movement of star-wheel 38 and disc 39, dog 37 engages one of the slots 40 and the tension of the main spring 12 causes wheel 31 to rotate rapidly until it is suddenly stopped when dog 37 again engages the periphery of disc 39. When this happens, spring 25 prevents the rest of the mechanism heretofore described from likewise suddenly stopping with the consequent strain on the parts. Instead, due to the resiliency of spring 25, pinion 21 and the gears connecting the same to the main spring 12 come to a more gradual stop and a great deal of strain is removed from the mechanism, thereby lessening the possibility of its getting out of order or requiring the replacement of parts. It may thus be seen that only upon partial rotation of star-wheel 38 and disc 39 may the actuating member 19 be rotated to operate the switch. It is therefore necessary to provide means for periodically rotating star-wheel 38 and disc 39 to permit the operation of the switch at definite and variable time intervals.

Stud shaft 41, upon which is mounted star-wheel 38 and disc 39, extends forwardly through the front of the clock casing as shown in Fig. 2, and on the outer end thereof may be provided a pair of intersecting levers or arms 42 and 43 as shown particularly in dotted lines in Fig. 1.

One of the arms 42 is preferably formed to lie closer to the outer front face of the clock casing than the arm 43 which is a greater distance therefrom. As the intersecting arms or levers 42 and 43 are rotated, the star-wheel 38 and disc 39 are rotated sufficiently to permit dog 37 to engage a slot 40 in the direction of the arrows as shown in Fig. 5, thus permitting wheel 31 to make one complete rotation which, with the proper arrangement of the gears and pinions, causes the switch to be operated. As two intersecting arms and levers are provided, shaft 41 is given no more than a ninety degree turn, which is only sufficient to cause a ninety degree rotation or less of star-wheel 38 and disc 39 and thereby prevents wheel 31 from making more than one complete rotation.

In order to manually rotate star-wheel 38 and disc 39 to permit operation of the switch whenever desired a pinion 41a is mounted on stud shaft 41 and meshes with pinion 42a mounted on a stud shaft 43a. A knob 44a is provided on the outer end of stud shaft 43a so as to be accessible through the hinged door 3.

A dial 44 is provided on the clock and is arranged to make one rotation in twenty four hours. 10 Dial 44 is mounted on a sleeve 45, the outer end of which is preferably tapered so that as the dial is moved inwardly on the sleeve 45 it more tightly binds the sleeve to prevent relative movement between them. A pair of hands or markers 46 and 15 47 are likewise mounted on sleeve 45 just beneath dial 44. The outer ends of the markers 46 and 47, which are preferably pointed at their ends, are bent upwardly and inwardly so that the inner ends thereof extend on top of the dial 44 and 20 serve to indicate the times at which the switch will be actuated. Each of the arms 46 and 47 is preferably provided with an inwardly extending portion 49 and 48, respectively which may be formed by cutting out a portion of the arms 46 25 and 47 and bending the same toward the clock mechanism. The inwardly extending portion 48 is preferably shorter than the inwardly extending portion 49, so that the former will ride over the lever 42 and only strike lever 43 to rotate 30 shaft 41. With this arrangement, the arms 46 and 47 may be set to operate the switch twice in each twenty-four hour period when two arms are employed. Arms 46 and 47 being mounted on the tapering sleeve 45, when properly positioned 35 as desired, will be held in place by tightening nut 50 which is threaded onto the outer end of sleeve 45. To prevent nut 50 from becoming unfastened, a second nut 51 is threaded on the outer end of sleeve 45 which acts to lock nut 50 against rotation with respect to sleeve 46.

The operation of the time-controlled switch 7 is as follows:

The hands or markers 46 and 47 are positioned to operate the switch at the desired times as 45 shown on the face of the dial. Upon rotation of sleeve 45 with dial 44 and arms 46 and 47, one of the inwardly projecting members 48 or 49 will engage one of the arms 42 or 43, thereby rotating shaft 41 no more than ninety degrees and star-wheel 38 and disc 39 on the end of shaft 41. This permits wheel 31 to make one complete rotation whereby the main spring 12 causes actuating member 19 to rotate a sufficient distance to operate the switch 7. The whole operation, due to the spring 25 in the arrangement of parts, is comparatively smooth with practically no sudden jarring, thus greatly increasing the life of the device. As the actuating member 19 is caused to rotate by main spring 12, the control mechanism is certain of operating as long as the clock runs.

Although the actuating member has been hereinbefore described as being operated by main spring 12, a separate spring might be provided for this purpose.

While there has been shown and described a preferred embodiment of the present invention, it will be apparent to those skilled in the art that 70 various changes and modifications may be made without departing from the spirit of the present invention and it is therefore wished that the invention be limited only by the scope of the prior art and the appended claims.

75 What is claimed is:

1. In a time-controlled construction comprising a member for being actuated, a rotatable toothed actuating member and means tending to cause continuous rotation of said actuating member, an escapement mechanism comprising a 5 shaft, a pinion on said shaft for engagement with said actuating member, a notched wheel on said shaft having a projecting member on the face thereof, means for connecting said pinion with said wheel, means for cooperating with said wheel to permit limited rotation thereof at predetermined intervals comprising a star-wheel having rounded concave portions for cooperating with the periphery of said first wheel, a disc rotatable with said star-wheel having notches 15 in the periphery thereof for registering with said projecting member on said first wheel, and time-controlled means for rotating said second wheel and disc at predetermined intervals.

2. In an escapement mechanism, the combination of a shaft, transmission means on said shaft, a notched wheel having a projecting member on the face thereof mounted on said shaft and connected with said transmission means, means tending to cause continuous rotation of 20 said transmission means and means for cooperating with said wheel to permit limited rotation thereof at predetermined intervals comprising a wheel having a concave portion in one side thereof for cooperating with the periphery of 25 said first wheel, a disc rotatable with said second wheel having a notch in the periphery for registering with said projecting member, and time-controlled means for rotating said second wheel and disc at predetermined intervals. 35

3. In an escapement mechanism, the combination of a shaft, transmission means on said shaft, a notched wheel having a projecting member on the face thereof mounted on said shaft and connected with said transmission means, 40 means tending to cause continuous rotation of said transmission means and means for cooperating with said wheel to permit limited rotation thereof at predetermined intervals comprising a star-wheel having the sides thereof formed to 45 cooperate with the periphery of said first wheel, a disc rotatable with said star-wheel having a notch in the periphery thereof for registering with said projecting member, and time-controlled means for rotating said second wheel and 50 disc at predetermined intervals.

4. In an escapement mechanism, the combination of a shaft, transmission means on said shaft, a notched wheel having a projecting member on the face thereof mounted on said shaft 55 and connected with said transmission means, means tending to cause continuous rotation of said transmission means and means for cooperating with said wheel to permit limited rotation thereof at predetermined intervals comprising a star-wheel having concavely rounded sides for cooperating with the periphery of said first wheel, a disc having a diameter greater than the diameter of said star-wheel rotatable with 60 said star-wheel, said disc having notches extending inwardly from the periphery in a direction opposite to the direction of rotation of said disc positioned so as not to register with said projecting member when said first wheel is in 70 engagement with a rounded surface of said star-wheel, and time-controlled means for rotating said disc and star-wheel at predetermined intervals a distance sufficient to permit said projecting member to register with one of said notches 75

whereby said first wheel may make one complete rotation.

5. In a time-controlled construction comprising a member for being actuated, a rotatable actuating member and means tending to cause continuous rotation of said actuating member, an escapement mechanism comprising transmission means, a notched wheel connected with said transmission means and having a projecting member on the face thereof, means for cooperating with said wheel to permit limited rotation thereof at predetermined intervals, comprising a rotating member having rounded concave portions for cooperating with the periphery of said first wheel, a disc for rotating with said rotatable member having a notch in the periphery thereof for registering with said projecting member on said first wheel, and time-controlled means for rotating said disk and rotatable member at predetermined intervals.
- 10 6. In an escapement mechanism the combination of transmission means, a notched wheel having a projecting member on the face thereof connected with said transmission means, means tending to cause continuous rotation of said

transmission means and means for cooperating with said wheel to permit limited rotation thereof at predetermined intervals, comprising a wheel having a concave portion in one side thereof for cooperating with the periphery of said first wheel; a disc rotatable with said second wheel, having a notch in the periphery thereof for registering with said projecting member, and time controlled means for rotating said second wheel and disc at predetermined intervals.

- 15 7. In an escapement mechanism a shaft, a pinion loosely mounted on said shaft, a wheel having a projecting member on the face thereof loosely mounted on said shaft, a coil spring positioned about said shaft, having one end connected to said pinion and the other end connected to said wheel, and rotating means for normally engaging said projecting member to prevent rotation thereof, said last means having a notch therein for permitting limited rotation of said wheel when said projecting member registers with said notch.

PHYLLIS C. HAYNES,
